[57] CLAIM

The ornamental design for a combined applicator and tampon, as shown and described.

DESCRIPTION

FIG. 1 is a front, side perspective view of a combined applicator and tampon, showing my new design, in non-use position;

FIG. 2 is a front elevational view thereof;

FIG. 3 is a rear elevational view thereof;

FIG. 4 is a side elevational view thereof, with all other sides being substantially identical thereto; and

FIG. 5 is a side elevational view in use position.
